CONDUCTOR SUPPORT

Ralph R. Pittman and Carroll H. Walsh, Pine Bluff, Ark.

Application January 23, 1939, Serial No. 252,323

6 Claims. (Cl. 248—65)

This invention relates generally to conductor supports, and particularly to a support adapted for supporting an uninsulated conductor normally operating a ground potential.

More specifically, the invention relates to a support having a pivotally mounted cradle for receiving the conductor, so that the cradle may move in response to vertical vibration of the conductor, and thereby prevent bending and subsequent fracture of the conductor near the support. Supports which function in the way are not new, but available supports of this character are provided with a clamp for tightly compressing the conductor. Since the material of the clamp members, for reasons of strength and economy, is steel or malleable iron, and the conductor is generally of copper or aluminum, the softer conductors are often damaged when clamped in place.

It is an object of the present invention to provide a conductor support embodying a cradle arranged for rocking movement in a vertical plane, having means for accommodating a tie wire for fastening the conductor to the cradle so that the assembly comprising the cradle, conductor and tie wire may rock about a pivotal mounting in response to vertical vibration of the conductor.

A further object is the provision of a rocking type of uninsulated conductor support having a minimum number of parts, which may be directly attached to pole or other supporting structures, and which is of improved construction and operation.

With these and other objects in view which will appear as the description proceeds, our invention resides in the combination, construction and arrangement of parts exemplified in the accompanying drawing and described in the following specification, and the scope of the invention is particularly pointed out on the appended claims.

In the drawing:

Fig. 1 is an elevation of an embodiment of the present invention, shown partly in section.

Fig. 2 is a top plan view of the invention also shown partly in section.

Fig. 3 is a front elevational view showing one arrangement of a conductor and tie wire in the service position on the support.

It may be seen from the drawing that our support consists of two parts or pieces, a base 10 and a cradle 16. The base 10 includes the vertically extending mounting portion 11, the portion 12 extending outwardly from the top of

the portion 11, and an upstanding portion 13, the latter being bifurcated at its upper end, and the ends of the bifurcations provided with a pair of axially aligned inwardly extending spaced pintles 14 and 15. An opening 26 is provided for cooperating with a fastening element for mounting the support on a pole.

The cradle 16 is provided with a pair of laterally spaced pockets 18, which extend upwardly into the cradle midway between its ends, and which are arranged to nest over the pintles 14 and 15 to pivotally support the cradle 16 on the base 10. The axis of pivotal movement of the cradle 16 with respect to the base 10 is substantially in horizontal alignment with the axis of 15 the conductor 24 when the latter is positioned in the longitudinally extending conductor-receiving groove 19, as shown in Fig. 3.

The end portions 20 and 21 of the cradle 16 extend downwardly a substantial distance below 20 the bottom of the conductor-receiving groove 19, in spaced relationship with the base 10, and have first inwardly and then outwardly curved portions forming a tie wire groove 22. As shown in Fig. 3, the conductor 24 may be secured to the cradle 16 25 by means of the tie wire 25, the latter being fastened to the conductor 24 and extending around the cradle 16 below the bottom of the conductor-receiving groove 19 and the pintles 14 and 15, and bearing on the inwardly and downwardly 30 sloping surfaces of the end portions 20 and 21. This arrangement enables the conductor 24 to be pulled tightly against the bottom of the conductor-receiving groove 19 by the tie wire 25. The convolutions of the tie wire 25 span the spaces 35 between the end portions 20 and 21, and are spaced from the upstanding portion 13 to avoid frictional engagement of these members.

From the above description, it will be seen that the assembly consisting of the cradle 16, the conductor 24, and the tie wire 25 are free to rock upon the pintles 14 and 15 in response to vertical vibrations of the conductor 24, within the limits permitted by the spacing of the lower ends of the end portions 20 and 21 from the upstanding portion 13.

While the cradle rests by gravity on the pintles, the contour of the conductor extending beyond the support may be such as to cause uplift on the cradle, tending to lift the cradle from the base. To avoid this occurrence, and for the further reason of convenience in shipping and handling, an outwardly extending portion 23 of the cradle 16 is positioned to engage the lower surface of the outer end of the pintle 14 in response 55

to an upward movement of the cradle. The lower surface of the portion 23 is preferably sloped inwardly and downwardly, so that the pintles are sprung apart sufficiently to permit attachment of the cradle when the portion 23 is pressed downwardly on the pintle.

This conductor support requires only two parts for its assembly, compared to the five to seven parts required in supports embodying bolted fasteners for attaching the conductor to the cradle.

10 The pivotal mounting permits vertical motion of the conductor at the point where it leaves the support, thereby avoiding bending and consequent fatigue fracture of the conductor. The 15 material of the tie wire is preferably the same as that of the conductor which it engages.

We realize that other embodiments of our invention will be apparent from the specific description of the particular embodiment recited 20 herein, and we wish it to be understood that our invention is to be limited only as may be necessitated by the prior art and the appended claims.

We claim, as our invention:

1. A two-part conductor support having a base 25 and a cradle pivotally mounted thereon, said cradle having a conductor-receiving groove extending across the top thereof and downwardly extending end portions having inwardly and downwardly curved external surfaces for providing a 30 bearing surface for engaging a tie wire which is fastened to the conductor.

2. A two-part conductor support having a base and a cradle pivotally mounted thereon, said cradle having a conductor-receiving groove extending across the top thereof, the end portions of said cradle extending downwardly, and the 35 downwardly extending end portions having inwardly and downwardly sloped surfaces to provide a bearing surface for a tie wire which is fastened to the conductor and wrapped around said 40 end portions.

3. A two-part conductor support having a base, a pair of axially aligned inwardly extending spaced pintles formed on said base portion, and 45 a cradle pivotally mounted on said pintles, said

cradle having a conductor-receiving groove extending across the top thereof, and means formed integral with said cradle for fastening said cradle to said pintles, said cradle having its respective ends extending downwardly below said groove, said end portions having inwardly and downwardly sloped external surfaces forming a bearing surface at the ends of said cradle for engaging a tie wire which is fastened to said conductor.

4. A two-part conductor support comprising a base portion, a portion integral with said base portion extending outwardly therefrom, and a pair of axially aligned pintles formed integrally with the outwardly extending portion, a cradle 15 mounted for rocking movement on said pintles, said cradle having a conductor-receiving groove extending longitudinally across the top thereof and end portions having inwardly and downwardly curved external surfaces which provide 20 a seating surface for a tie wire fastened to the conductor.

5. A two-part conductor support comprising an upstanding portion having a pair of axially aligned inwardly extending pintles, a conductor-receiving cradle having pockets engaging said pintles and arranged for rocking movement thereon, and means formed integral with said cradle for fastening said cradle to said upstanding portion, said cradle having portions extending downwardly from said pockets, and inwardly extending grooves in the downwardly extending portions for receiving a tie wire.

6. A two-part conductor support consisting of an upstanding portion and a cradle pivotally mounted thereon, and means integral with said cradle for fastening said cradle to said base portion, said cradle having a portion extending downwardly along said upstanding portion in spaced relationship therewith, and a horizontally positioned peripheral groove extending inwardly along the downwardly extending portion of said cradle.
